UNITED STATES PATENT OFFICE.

GEORGE A. BURNHAM, OF SAUGUS, MASSACHUSETTS, ASSIGNEE, BY MESNE ASSIGNMENTS, TO CONDIT ELECTRICAL MANUFACTURING CORPORATION, OF BOSTON, MASSACHUSETTS, A CORPORATION OF MASSACHUSETTS.

ATTACHMENT FOR ELECTRIC SWITCHES.

Application filed May 14, 1920. Serial No. 391,466.

To all whom it may concern:

Be it known that I, GEORGE A. BURNHAM, a citizen of the United States, residing at Saugus, in the county of Essex and State of Massachusetts, have invented an Improvement in Attachments for Electric Switches, of which the following is a specification.

This invention relates to electric switches of the oil immersed type adapted to control and interrupt alternating current circuits carrying relatively high values of current.

In a co-pending application, Serial No. 309,853, filed July 10, 1919, on which application Patent No. 1,413,156, dated April 18, 1922, has issued, I have disclosed an electric switch having means to absorb energy developed upon circuit interruption comprising a fixed switch frame and an oil receptacle enclosing the switch members resiliently and removably carried by said frame, also having a second receptacle or "spill" tank adapted to contain the oil receptacle of the switch and catch oil expelled therefrom upon circuit interruption.

In another co-pending application Serial No. 374,276, filed April 16, 1920, I have set forth an electric switch having a resiliently and removably supported oil receptacle and also a spill tank differently constructed and arranged yet adapted to accomplish the same result.

The object of my present invention is to provide an oil receptacle with resilient and removable supporting means, and also when desired, a spill tank, as an attachment for an electric switch.

Fig. 1 is a side elevation of my invention applied to an electric switch constructed as set forth in my co-pending application, Serial No. 309,853, filed July 10, 1920.

Fig. 2 is a transverse section of the switch of Fig. 1.

Fig. 3 is a transverse section of a modified form of switch having the attachment applied thereto.

Fig. 4 is a sectional elevation illustrating the attachment applied to a three-phase switch having individual oil receptacles per phase.

Fig. 5 is a transverse sectional view of the attachment of Fig. 1 separate from the switch.

Fig. 6 is a transverse sectional view of the attachment without the spill receptacle.

Fig. 7 is a transverse sectional view of the spill receptacle alone applied to a switch.

Fig. 8 is a side elevation of the attachment applied to a three-phase switch.

Fig. 9 is a sectional detail of means for removably securing the attachment yielding to the switch frame.

Figs. 10 and 11 are sectional details illustrating modified forms of attaching means.

Fig. 12 is a sectional detail of a modified arrangement for removably securing the attachment illustrated in Figs. 5 and 6 yielding to the switch frame.

As here shown, an electric switch adapted to receive my attachment has the fixed switch frame 10, comprising a cover for the oil receptacle, with the arm 11 extended therefrom by which the switch may be secured to a fixed support. Stationary switch members 12 and movable switch members 13 are carried by the switch frame and depend therebelow to be immersed in the oil contained in the oil receptacle. The switch operating mechanism 14 is also carried by the switch frame.

The switch frame is formed with a peripherally depending lip or flange for the purpose of centering the oil receptacle and for preventing the creepage of moisture into the switch. The depending flange additionally may serve to support the side walls of the oil receptacle and to guide the gases expelled from the switch upon circuit interruption in a downward direction. The depending flange 15, in Figs. 1 and 2, illustrates the type adapted to support the oil receptacle and also to guide the expelled gas downwardly; and the flange or lip 16, in Figs. 4, 11 and others, illustrates the type adapted merely to center the oil receptacle and prevent creepage of moisture into the switch.

The attachment embodying my invention includes the oil receptacle 20 adapted to be placed in position on the switch with its side walls within the flange 15 or lip 16 of the switch and to contain the switch members which will be immersed in the oil contained therein.

The attachment also comprises the outer

receptacle or spill tank 21 which preferably is adapted to extend above the flange or lip and to be peripherally spaced from the switch frame to provide a vent *a* for the final escape of uncondensed gas or vapor from the switch to the atmosphere.

The oil receptacle 20 is adapted to be contained with the outer or spill receptacle 21 and the side walls of the two receptacles are spaced from each other, preferably at least for the greater part of their peripheral extent, a relatively narrow distance to provide a space *b* therebetween to serve as a condensation chamber to receive condensable vapor and gas expelled from the switch thereof. The condensed oil or other vapor will collect at the bottom of the outer receptacle. Said space *b* between the two receptacles is relatively narrow as compared with its depth whereby combustion will not be supported therein.

In some forms of the attachment embodying my invention, I prefer to secure the inner receptacle to the outer receptacle as by spot welding the bottom of the two receptacles together whereby to form a unitary structure. In other forms the inner receptacle may be loosely received within the outer receptacle and no particular means for securing the two receptacles together will be provided. I may, however, employ means to center the inner receptacle within the outer receptacle as, for instance, the strip of angle iron 22 arranged in the bottom of the spill receptacle as illustrated in Figs. 1 and 2.

The inner oil receptacle may be a single oil receptacle as illustrated in Figs. 1 and 2 or it may be formed with a plurality of partitions therein to form as many sections as there are phases in the circuit controlled by the switch; or there may be an individual oil receptacle per switch pole.

In Fig. 4 I have illustrated a switch having three poles 12^a, 12^b, and 12^c adapted for the control of a three phase circuit. I have also shown three individual oil receptacles 20^a, 20^b and 20^c, each adapted to receive a pole of the switch. This is in accordance with the present standard construction. Each of the oil receptacles may be provided with independent spill receptacles as above set forth or all of the individual receptacles may be contained within a single spill receptacle. Fig. 4 illustrates the single spill receptacle 21 containing all of the oil receptacles. The oil receptacles are herein united to the spill receptacle by suitable means as spot-welding, and said latter receptacle is supported from the switch frame through the oil receptacles by means of the bolts 23 which are secured to the side walls of the oil receptacles and extended through apertures in the switch frame. Compression springs 24 encircle said bolts above said switch frame and wing nuts 25 removably

threaded on said bolts compress said springs against the switch frame. By this construction the attachment is resiliently supported from the frame and the attachment may be removed by removing the said wing nuts. 70

In said Fig. 4, said bolts 23 are extended through said switch frame beyond the depending flange or lip 16. In Fig. 3 the same arrangement of attaching means is illustrated but said bolts 23 extend through the switch frame on the inside of said flange or lip. The switch frame illustrated in Fig. 3 is also provided with a second rib 26 adapted to fit within the outer wall of and center the oil receptacle. 80

In Figs. 1 and 2, I have illustrated a form of attaching and supporting means for my attachment which I prefer to employ when the construction of the switch will permit of its use. The two receptacles 20 and 21 are supported on the grids 27, or it may be one grid, which extend on opposite sides beyond the periphery of the outer receptacle. Rods 28 are fixed to such extended portions of the grid and extended upward on each side of the outer receptacle. The upper ends of said rods are slidably received in holes in lugs 29 which are extended from the switch frame 10 beyond said flange 15. Said lugs preferably have the recess 30 therein. Compression springs 31 are received in said recesses 30 and encircle the upper ends of said rods 28. The upper ends of said rods are threaded and nuts 32 are removably received thereon and serve to 95 compress the spring 31 between them and the bottom walls of the recess. By this arrangement, the attachment is yieldingly supported from the switch frame and may be detached therefrom by the removal of said nuts 32. Sleeves 33 are fixed to said rods 28 by suitable means and are arranged below said lugs 29 and for certain forms of the attachment serve to engage the ends of said lugs 33 to limit the upward movement 100 of the oil receptacle and provide a clearance space between the top of the oil receptacle and the under side of the switch frame for the purpose of permitting escape of gas and vapor from the switch over the top of the oil receptacle and downwardly between the outer periphery of the oil receptacle and the flange 15. The oil receptacle 20 for such an arrangement is made somewhat less than the dimensions bounded by said flange 14 115 where a relatively narrow passage *c* is provided therebetween for the downward escape of gas. For some purposes, however, I may desire to have the top of the oil receptacle 20 retained yieldingly in substantial contact with the inside of the switch frame 120 whereby to provide a substantially closed or non-vented switch, yet it is understood that there will be sufficient irregularity of contact between the oil receptacle and the switch 125 130

frame to provide small clearance spaces through which the switch is enabled to breathe. With such an attachment, I may omit the sleeves 33 entirely or so dispose of them on said rods 28 that said springs 30 serve yieldingly to maintain the top of the oil receptacle 20 directly in contact with the switch frame.

For some purposes, I provide, as the attachment, the oil receptacle and the outer or spill receptacle, with suitable attaching means, as illustrated in Fig. 5. I may, however, omit the spill receptacle and support the oil receptacle alone removably and yieldingly about the switch members. This feature of the attachment is illustrated in Fig. 6 and is substantially the same as the attachment illustrated in Fig. 5 with the exception that the spill receptacle 21 is absent. My invention also contemplates the employment of the spill receptacle by itself as an attachment to an electric switch and in Fig. 7 I have illustrated such an attachment applied to the electric switch. In said figure, the spill tank 21 contains the oil receptacle 20 of the switch as before but the two receptacles are entirely independent and to emphasize such independence, I have illustrated the outer receptacle 21 as being entirely clear of the inner receptacle. The inner receptacle is supported in its usual manner by the bolts 23 extending through the switch frame 10 and secured thereto by the nuts 25. The outer oil receptacle or spill tank 21 is independently secured to the switch frame and as a convenient means for doing this I provide the bars or straps 35 which have apertures therein through which the rods or bolts 23 are extended. The nuts 25 on said rods or bolts 23 serve to secure said bars 35 firmly to the switch frame and said bars are extended outwardly therefrom. Said outer receptacle is provided with bolts 36 which are extended through apertures in the end-portion of said bars and are secured thereto by the nuts 37 removably threaded on said bolts.

Fig. 12 illustrates a modification of the arrangement illustrated in Fig. 7 wherein the oil receptacle and the spill tank are both removably and yieldingly supported from the switch frame. The rods 28 in this modification extend through apertures in said bars 35, which bars are secured to the switch frame by the bolts 39. Springs 31 are disposed over said extended ends of said rods 28 and rest upon said bars. Wing nuts 40 are removably threaded on the extended ends of said rods engage said springs whereby the attachment is resiliently and removably supported from the switch frame.

Fig. 10 illustrates a modified form of means for securing the attachment to the switch frame wherein the bolt 41 is fixed by

rivets 42 on the inside of the wall of the receptacle 20 and extends upwardly through the frame 10 within the lip. A spring 24 and nut 25 is arranged on the bolt as in Fig. 4.

In Fig. 11 the attaching bolt 42 is secured in the bolt member 43 fixed to the outer periphery of the oil receptacle and said bolt extends through a lug 44 of the switch frame beyond the lip 16.

In Fig. 9, a lug 45 is fixed to the inner periphery of the oil receptacle 20 slightly below the top of the receptacle. A bolt 46 is slidably received in an aperture therein and extends therethrough. A spring 47 encircles said extended portion of the bolt 46 and engages the head 48 of the bolt and said lug 45. Said bolt extends through an aperture in the switch frame and a wing nut 49 is threaded thereon. By this arrangement, the attachment is resiliently and removably secured to the switch frame and said springs 47 are enclosed within the receptacle.

The outer receptacle, in all the modifications, is preferably adapted to extend above the lower edge of the depending lip or flange of the switch for at least for the greater portion of its peripheral extent whereby the more effectively to collect oil and condense gas and vapor expelled from the switch.

I claim:

1. An attachment for a multi-pole electric switch comprising a plurality of oil receptacles each adapted to contain the switch members comprising a switch pole, an outer receptacle containing said oil receptacles adapted to catch oil expelled therefrom, and means removably to support the attachment in position about the switch members.

2. An attachment for a multi-pole electric switch comprising a plurality of oil receptacles each adapted to contain the switch members comprising a switch-pole, an outer receptacle containing said oil receptacles adapted to catch oil expelled therefrom, and means removably to support the attachment yieldingly in position about the switch members.

3. An attachment for a multi-pole electric switch comprising a plurality of oil receptacles each adapted to contain the switch members comprising a switch-pole, an outer receptacle containing said oil receptacles adapted to catch oil expelled therefrom, and means yieldingly to support the attachment in position about the switch members.

4. A multi-pole electric switch comprising a switch frame, a plurality of switch members grouped in poles depending therefrom, individual oil receptacles per pole depending from said frame, and a receptacle dis-

posed below said switch frame and containing all of said oil receptacles and adapted to catch oil expelled therefrom.

5. A multi-pole electric switch comprising a switch frame, a plurality of switch members grouped in poles depending therefrom, individual oil receptacles per pole removably depending from said frame, and a receptacle removably disposed to contain 10 all of said oil receptacles and to catch oil expelled therefrom.

6. A multi-pole electric switch comprising a switch frame, a plurality of switch members grouped in poles depending therefrom, individual oil receptacles per pole 15 removably and yieldingly depending from said frame, and a receptacle disposed below said switch frame and containing all of said oil receptacles and adapted to catch 20 oil expelled therefrom.

7. A multi-pole electric switch comprising a switch frame, a plurality of switch members grouped in poles depending therefrom, individual oil receptacles per pole 25 depending from said frame, a receptacle containing all of said oil receptacles adapted to catch oil expelled therefrom and means to secure said oil-catching receptacle yieldingly to said switch frame.

8. A multi-pole electric switch comprising 30 a switch frame, a plurality of switch members grouped in poles depending therefrom, individual oil receptacles per pole, a receptacle containing all of said oil receptacles adapted to catch oil expelled therefrom, and means removably to secure all 35 said receptacles to said switch frame.

9. A multi-pole electric switch comprising 40 a switch frame, a plurality of switch members grouped in poles depending therefrom, individual oil receptacles per pole, a receptacle containing all of said oil receptacles adapted to catch oil expelled therefrom, and means removably to secure all 45 said receptacles yieldingly to said switch frame.

10. A multi-pole electric switch comprising 50 a switch frame, a plurality of switch members grouped in poles depending therefrom, individual oil receptacles per pole, a receptacle containing all of said oil receptacles adapted to catch oil expelled therefrom, and means yieldingly to secure all 55 said receptacles to said switch frame.

In testimony whereof, I have signed my 55 name to this specification.

GEORGE A. BURNHAM.
